DESIGN FOR A COMBINED GRATER AND CUTTER

Edna N. Higginbotham, Long Beach, Calif.

Application October 10, 1939, Serial No. 87,608

Term of patent 3½ years

To all whom it may concern:

Be it known that I, Edna N. Higginbotham, a citizen of the United States, residing at Long Beach, in the county of Los Angeles and State of California, have invented a new, original, and ornamental Design for a Combined Grater and Cutter, of which the following is a specification, reference being had to the accompanying drawing, forming a part thereof.

I claim:

The ornamental design for a combined grater and cutter, as shown.

EDNA N. HIGGINBOTHAM.
